US00D612856S

(12) **United States Design Patent**
Wahl et al.

(10) **Patent No.:** **US D612,856 S**
(45) **Date of Patent:** **** Mar. 30, 2010**

(54) **CONNECTOR FOR A PERIPHERAL DEVICE**

(75) Inventors: **James Wahl**, Export, PA (US); **Chris Nightingale**, Wimbledon (GB)

(73) Assignee: **Vocollect Healthcare Systems, Inc.**, Pittsburgh, PA (US)

(**) Term: **14 Years**

(21) Appl. No.: **29/331,318**

(22) Filed: **Jan. 23, 2009**

Related U.S. Application Data

(63) Continuation-in-part of application No. 29/303,922, filed on Feb. 20, 2008, now Pat. No. Des. 585,896.

(51) **LOC (9) Cl.** **14-02**

(52) **U.S. Cl.** **D14/433**

(58) **Field of Classification Search** **D14/356-358, D14/383-385, 432-439, 442, 447, 451, 453, D14/474, 155, 217, 242, 299; D13/107, D13/108, 118, 120, 123, 133, 146, 147, 154, D13/158, 182, 184, 199; 361/679, 685, 686, 361/724-728, 683, 639; 439/668, 669, 701, 439/660, 607, 296; 455/351, 353, 325**

(57) **CLAIM**

The ornamental design for a connector for a peripheral device, as shown and described.

DESCRIPTION

FIG. 1 is a front perspective view of the invention, with broken lines showing a mobile device to which the connector of the invention is connected;

FIG. 2 is another perspective view of the invention of FIG. 1;

FIG. 3 is a front elevational view of the invention of FIG. 2;

FIG. 4 is a rear elevational view of FIG. 2;

FIG. 5 is a right side elevational view of FIG. 2;

FIG. 6 is a left side elevational view of FIG. 2;

FIG. 7 is a top view of FIG. 2; and,

FIG. 8 is a bottom view of FIG. 2.

The broken line showing of the mobile device and other features in the Figures is included for the purpose of illustrating environmental structure and forms no part of the claimed design. The portions of the connector for a peripheral devices illustrated in broken lines form no part of the claimed design.

1 Claim, 2 Drawing Sheets
